UNITED STATES PATENT OFFICE.

SAMUEL SEIDES, OF NEW YORK, N. Y.

DESIGN FOR A BADGE.

Application filed May 28, 1928. Serial No. 26,884. Term of patent 14 years.

To all whom it may concern:

Be it known that I, SAMUEL SEIDES, a citizen of the United States, residing at 1939 Seventy-fifth St., in the county of Kings and State of New York, have invented a new, original, and ornamental Design for Badge, of which the following is a specification, reference being had to the accompanying drawing, forming part thereof.

I claim:

The ornamental design for a badge as shown.

SAMUEL SEIDES.
